CLAIM

The ornamental design for a display panel of a programmed computer system with a graphical user interface, as shown and described.

DESCRIPTION

FIG. 1 is a first view of a display panel of a programmed computer system with a graphical user interface;

FIG. 2 is a second view thereof;

FIG. 3 is a third view thereof;

FIG. 4 is a fourth view thereof;

FIG. 5 is a fifth view thereof;

FIG. 6 is a sixth view thereof;

FIG. 7 is a seventh view thereof;

FIG. 8 is an eighth view thereof; and,

FIG. 9 is a ninth view thereof.

The broken line showing of a display panel with a graphical user interface is included for the purpose of illustrating portions of the article and forms no part of the claimed design.

The appearance of the transitional image sequentially transitions between the images shown in FIGS. 1-9. The process or period in which one image transitions to another image forms no part of the claimed design.
